UNITED STATES PATENT OFFICE.

FRED HENRY GILE, OF CLIFTONDALE, MASSACHUSETTS, ASSIGNOR, BY MESNE ASSIGNMENTS, TO GEORGE K. WOODWORTH, TRUSTEE, OF BROOKLINE, MASSACHUSETTS.

INTERNAL-COMBUSTION ENGINE.

1,335,329.

Specification of Letters Patent. Patented Mar. 30, 1920.

Original application filed July 25, 1917, Serial No. 182,609. Divided and this application filed June 27, 1918. Serial No. 242,320.

To all whom it may concern:

Be it known that I, FRED HENRY GILE, a citizen of the United States, and a resident of Cliftondale, in the county of Essex and State of Massachusetts, have invented a new and useful Improvement in Internal-Combustion Engines, of which the following is a specification.

My invention relates to internal combustion engines and its objects are to improve and simplify the construction thereof and increase the efficiency of the same in the manner hereinafter set forth.

In an earlier application (Serial No. 19,265, filed April 5, 1915) I have disclosed means for effecting a substantially complete combustion of the charge of fuel and air, said means comprising a relatively large number of fuel passages through which the charge is forced under pressure to the combustion chamber thereby thoroughly, intimately and completely mixing the same. I have discovered that it is not necessary to sub-divide the charge in the manner set forth in said application in order to effect perfect mixing and complete combustion, and that these results can be accomplished by forcing the charge under pressure into the combustion chamber in the form of a thin cylindrical or annular sheet instead of a number of small streams.

In the present application, which is a division of my application Serial No. 182,609, filed July 25, 1917, I show and claim an engine having a cylinder of uniform diameter wherein the fuel charge is drawn into the space between the power piston and the sub-piston on one stroke and forced into the combustion chamber around the head of the sub-piston in a thin cylindrical or annular sheet on the other stroke.

The accompanying drawings show one embodiment of the present invention but it is to be understood that various modifications may be made therein and various other arrangements devised for forcing the charge into the combustion chamber in the form of a thin cylindrical sheet without departing from the scope of my invention as defined by the appended claims.

In the drawings—

Figure 1 is a central vertical section of an engine embodying my invention. Fig.

2 is a section taken on the line 2—2 of Fig. 1. Fig. 3 is a plan view of the cylinder 55 with the head removed.

In the particular drawings selected for more fully disclosing my invention 1 is a cylinder suitably secured to the crank casting and the upper end thereof is counterbored at 2, the bottom of said counterbore preferably being beveled inwardly. Arranged to reciprocate within the cylinder is a power piston 3, and the two-part pitman 4 engaging the pin 5 secured in the walls 60 thereof, connects the same to the crank 6. A sub-piston 7 is arranged to reciprocate within the cylinder between the power piston and the combustion chamber, and its rod 8 passes through and is guided by the 65 central core of the power piston, its lower end being pivotally connected to the double link 9 which in turn engages the arm 10 of the rock shaft 11 journaled in the sides of the frame and passing across the latter 75 above the crank shaft and to the rear thereof.

A rod 12 connects the shorter arm 13 on said rock shaft with the arm 14 integral with the rock shaft 15 which is journaled 80 between the frame and the block 16 which rises from the base thereof. The hub 17 of the connecting rod 18 is in engagement with the wrist pin of the crank 6, being arranged between one arm of said crank and the box 85 of the pitman 4, and said rod is pivotally connected with the longer arm 19 of the rock shaft 15. The sub-piston therefore is controlled positively throughout the entire cycle.

The cylinder has an exhaust passage 20 controlled by the valve 21 normally held to its seat by the spring 22 which surrounds the valve stem 23 and bears against the valve housing and the collar 24 on said 95 stem. The valve may be opened by any suitable mechanism such for example as the tappet 25 actuated by the cam 26 which operates with the head 27 thereof.

The fuel inlet 28 is located a short distance above the lower end of the power piston when the power piston is in explosion position at the end of its upstroke as shown in Fig. 2.

In this construction it is essential that 105 there should be a gas-tight joint between

the sub-piston and the cylinder, and to this end the sub-piston is provided with the usual piston ring 29.

In order to prevent the ring from springing out of its groove when the sub-piston projects into the counterbored end of the cylinder I provide as shown an undercut ring 30 which may be screwed to the upper face of the sub-piston and the depending outer edge of which engages the rabbeted portion of the piston ring. It will be obvious that various other equivalent means may be devised for holding the ring in position without destroying its freedom of movement which is essential to the performance of its function.

I do not limit myself as to the depth of the counterbore 2 or to the area between the peripheral surface of the sub-piston and the wall of the counterbored portion of the cylinder,—in other words, to the thickness of the cylindrical sheet in which the charge passes to the combustion chamber. It must be sufficiently thin to effect such a thorough mixing of the charge that substantially complete combustion will result on ignition. If it is too thin, the back pressure will be excessive. If it is too thick the mixing will not be thorough and the resulting combustion will not be complete or substantially complete. No hard and fast rule can be given as to the depth of said counterbore which will give the best results under all conditions of operation and for all kinds of fuel. I have found however that in a cylinder having a four inch bore and a five inch stroke, the counterbore 2 may be one-sixty-fourth of an inch, two-sixty-fourths of an inch, three-sixty-fourths of an inch, or four-sixty-fourths of an inch. I believe that good results could be obtained in such cylinder if the counterbore exceeded in depth four-sixty-fourths of an inch. I have found that in the engine above referred to the best results were obtained with a counterbore three-sixty-fourths of an inch deep. In that case the area inclosed between the wall of the counterbored portion of the cylinder and the periphery of the sub-piston was almost exactly equal to one-half of the area of the intake port. I believe therefore that this area depends in a way upon the volume of the cylinder and upon the cross sectional area of the intake port. I believe also that this area must be such, due regard being had to the cubical contents of the cylinder and the cross sectional area of the intake port, that sufficient restraint will be imposed to the passage of the gas through the counterbore as to enable the same to acquire a relatively high velocity during such passage.

As shown, the bottom of the counterbore preferably is beveled inwardly so as to prevent undue heating of the square corner

that would exist were the bottom of the counterbore at right angles to the wall thereof.

The operation is as follows: When the pistons are at the upper end of their strokes (explosion position) as shown in Figs. 1 and 2, the charge is fired and both pistons descend at the same initial rate of speed without any relative movement until the crank which rotates in the direction of the arrow (Fig. 2) has reached a point a little less than 135° from initial position whereupon the sub-piston having reached substantially the end of its down-stroke begins to lag and the power piston continuing its descent moves away therefrom until the crank has arrived at about 135° from its explosion position. The sub-piston is then at the lower end of its stroke with its upper face just above the fuel inlet 28 and the upper face of the power piston is just below said inlet. Further rotation of the crank causes the power piston to continue its down-stroke and the sub-piston to begin its upstroke. The relative movement between the pistons creates a vacuum in the space between them into which a charge of fuel is drawn through the inlet 28. The exhaust valve 21 opens practically simultaneously with or preferably shortly before the commencement of the upstroke of the sub-piston and the burnt gases of the preceding explosion are expelled by the latter, which thereby prevents the admixture of the next charge with said burned gases. When the crank has arrived at about 240° from initial position the sub-piston has reached explosion position and from this point until the crank returns to initial position and the power piston assumes the position shown in Fig. 2 the sub-piston remains substantially stationary. As soon as the power piston on its upward stroke covers the fuel inlet, it begins to compress the charge in the space between the pistons, and a portion of the charge so compressed passes around the head of the sub-piston through the counterbored end of the cylinder to the combustion chamber thereby assisting the scavenging of the latter before the exhaust valve closes. The power piston continuing its upward stroke further compresses the charge and expels the same from the space between the pistons through the space between the sub-piston and the counterbored end of the cylinder into the combustion chamber thereby thoroughly mixing the same. When the parts have again assumed the position shown in Fig. 2 the entire charge has been forced into the combustion chamber in the form of a thin cylindrical or annular sheet whereupon ignition occurs and the cycle is repeated.

It will be noted that the compression of the charge is continuous and increases progressively until the power piston reaches the

end of its stroke, and that the charge is not permitted to expand after having reached its maximum pressure until it is fired.

It will be obvious that by duplicating the 5 sub-piston control apparatus shown in Figs. 1 and 2, *i. e.*, the system of links and rock-shafts which govern the movement of the sub-piston to which apparatus I make no claim, my invention may be applied to a 10 double acting engine having two sub-pistons, one on either side of the power piston.

I claim:

1. An internal combustion engine, comprising in combination a cylinder, a power-piston and a sub-piston both arranged to reciprocate therein, the combustion-chamber end of said cylinder being counterbored, a rabbeted ring in a groove in the peripheral surface of said sub-piston, and an undercut 20 ring secured to the upper face of said sub-piston and having its depending outer edge in engagement with the rabbeted portion of said ring.

2. An internal combustion engine, comprising in combination a cylinder, a power-piston and a sub-piston both arranged to reciprocate therein, the combustion-chamber end of said cylinder being counterbored, a rabbeted ring in a groove in the peripheral 30 surface of said sub-piston, and means secured to said sub-piston for preventing said ring from springing out of its groove.

3. An internal combustion engine, comprising in combination a cylinder, a power-piston and a sub-piston both arranged to reciprocate therein, the combustion-chamber end of said cylinder being counterbored, a ring in a groove in the peripheral surface of said sub-piston, and means for maintaining 40 said ring in its groove.

4. An internal combustion engine, comprising in combination a cylinder having a combustion chamber, means whereby a charge of fuel and air is drawn into said cylinder, means whereby said charge is forced under pressure into said combustion chamber in the form of a hollow cylinder, the walls of which are sufficiently thin to effect such a thorough mixing of said charge 50 that substantially complete combustion will result on ignition, a valveless sub-piston for preventing said charge from commingling with the burned gases of the previous explosion and means for controlling said sub-piston positively throughout the entire cycle.

5. An internal combustion engine, comprising in combination a cylinder having a combustion chamber, means whereby a charge of fuel and air is drawn into said cylinder, means whereby said charge is forced under pressure into said combustion chamber in a thin annular sheet, a valveless sub-piston for preventing said charge from commingling with the burned gases of the 60 previous explosion and means for control-

ling said sub-piston positively throughout the entire cycle.

6. An internal combustion engine, comprising in combination a cylinder having a combustion chamber, means whereby a 70 charge of fuel and air is drawn into said cylinder, means whereby said charge is forced under pressure into said combustion chamber in an annular sheet sufficiently thin to effect such a thorough mixing of 75 said charge that substantially complete combustion will result on ignition, a valveless sub-piston for preventing said charge from commingling with the burned gases of the previous explosion and means for controlling 80 said sub-piston positively throughout the entire cycle.

7. An internal combustion engine, comprising in combination a cylinder terminating in a combustion chamber, the combustion-chamber end of said cylinder being counterbored, a power piston arranged to reciprocate in said cylinder, a sub-piston located between said power piston and said combustion chamber, the area between the 90 peripheral surface of said sub-piston and the wall of the counterbored portion of the cylinder being so small that a charge of fuel and air may be forced therethrough into the combustion chamber in an annular sheet 95 sufficiently thin to effect such a thorough mixing of said charge that substantially complete combustion will result on ignition, and means for controlling said sub-piston positively throughout the entire cycle.

8. An internal combustion engine, comprising in combination a cylinder terminating in a combustion chamber, the combustion-chamber end of said cylinder being counterbored, a power piston arranged to reciprocate in said cylinder, a sub-piston located between said power piston and said combustion chamber, and means for controlling 105 said sub-piston positively throughout the entire cycle.

9. An internal combustion engine, comprising in combination a cylinder terminating in a combustion chamber, the combustion-chamber end of said cylinder being counterbored, a power piston arranged 115 to reciprocate in said cylinder, a sub-piston located between said power piston and said combustion chamber, a shaft having a crank, a pitman connecting said power piston to said crank, and means actuated directly by said crank for controlling said sub-piston positively throughout the entire cycle.

10. An internal combustion engine, comprising in combination a cylinder terminating in a combustion chamber, the combustion-chamber end of said cylinder being counterbored, a power piston arranged to reciprocate in said cylinder, a sub-piston located between said power piston and said 125

combustion chamber, the area between the peripheral surface of the sub-piston and the wall of the counterbored portion of the cylinder being so small that a charge of fuel and air may be forced therethrough into the combustion chamber in a cylindrical sheet sufficiently thin to effect such a thorough mixing of such charge that substantially complete combustion will result on ignition, and means for controlling said sub-piston positively throughout the entire cycle.

11. An internal combustion engine, comprising in combination a cylinder terminating in a combustion chamber, a power piston arranged to reciprocate in said cylinder, a valveless sub-piston located between said power piston and said combustion chamber, the area between the peripheral surface of said sub-piston and the wall of the cylinder at the combustion-chamber end thereof being so small that a charge of fuel and air may be forced therethrough into the combustion chamber in an annular sheet sufficiently thin to effect such a thorough mixing of such charge that substantially complete combustion will result on ignition, and means for controlling said sub-piston positively throughout the entire cycle.

12. An internal combustion engine, comprising in combination a cylinder having a combustion chamber, a power piston arranged to reciprocate in said cylinder, a valveless sub-piston arranged between said power piston and said combustion chamber, said sub-piston constituting means whereby a charge of fuel and air is drawn into said cylinder and also means for preventing said charge from commingling with the burned gases of the previous explosion, means whereby said charge is forced under pressure into said combustion chamber in an annular sheet sufficiently thin to effect such a thorough mixing of said charge that substantially complete combustion will result on ignition, and means for controlling said sub-piston positively throughout the entire cycle.

13. An internal combustion engine, comprising in combination a cylinder having a combustion chamber, a power piston arranged to reciprocate in said cylinder, a valveless sub-piston arranged between said power piston and said combustion chamber, said sub-piston constituting means whereby a charge of fuel and air is drawn into said cylinder, means whereby said charge is forced continuously and with progressively increasing pressure into said combustion chamber in an annular sheet sufficiently thin to effect such a thorough mixing of said charge that substantially complete combustion will result on ignition, and means for controlling said sub-piston positively throughout the entire cycle.

14. An internal combustion engine, comprising in combination a cylinder terminating in a combustion chamber, the combustion-chamber end of said cylinder being counterbored, a power piston arranged to reciprocate in said cylinder, a sub-piston located between said power piston and said combustion chamber, a ring in a groove in the peripheral surface of said sub-piston means for maintaining said ring in said groove, the area between the peripheral surface of said sub-piston and the wall of the counterbored portion of the cylinder being so small that a charge of fuel and air may be forced therethrough into the combustion chamber in an annular sheet sufficiently thin to effect such a thorough mixing of said charge that substantially complete combustion will result on ignition, and means for controlling said sub-piston.

15. An internal combustion engine, comprising in combination a cylinder terminating in a combustion chamber, the combustion-chamber end of said cylinder being counterbored, a power piston arranged to reciprocate in said cylinder, a sub-piston located between said power piston and said combustion chamber, a ring in a groove in the peripheral surface of said sub-piston, means for maintaining said ring in said groove, and means for controlling said sub-piston.

16. An internal combustion engine, comprising in combination a cylinder terminating in a combustion chamber, the combustion-chamber end of said cylinder being counterbored, a power piston arranged to reciprocate in said cylinder, a sub-piston located between said power piston and said combustion chamber, a ring in a groove in the peripheral surface of said sub-piston, means for maintaining said ring in said groove, a shaft having a crank, a pitman connecting said power piston to said crank, and means actuated directly by said crank for controlling said sub-piston positively throughout the entire cycle.

17. An internal combustion engine, comprising in combination a cylinder terminating in a combustion chamber, the combustion-chamber end of said cylinder being counterbored, a power piston arranged to reciprocate in said cylinder, a sub-piston located between said power piston and said combustion chamber, a ring in a groove in the peripheral surface of said sub-piston, means for maintaining said ring in said groove, and means for controlling said sub-piston positively throughout the entire cycle.

18. An internal combustion engine, comprising in combination a cylinder of uniform diameter having a combustion chamber, means whereby a charge of fuel and air is drawn into said cylinder, means whereby

said charge is forced under pressure into the combustion chamber in the form of a hollow cylinder, the walls of which are sufficiently thin to effect such a thorough mixing of said charge that substantially complete combustion will result on ignition, a valveless sub-piston for preventing said charge from commingling with the burned gases of the previous explosion, and means for controlling 10 said sub-piston.

19. An internal combustion engine, comprising in combination a cylinder of uniform diameter having a combustion chamber, means whereby a charge of fuel and air is drawn into said cylinder, means whereby said charge is forced under pressure into said combustion chamber in a thin annular sheet, a valveless sub-piston for preventing said charge from commingling with the 15 burned gases of the previous explosion, and means for controlling said sub-piston.

20. An internal combustion engine, comprising in combination a cylinder of uniform diameter having a combustion chamber,

25
is drawn into said cylinder, means whereby said charge is forced under pressure into said combustion chamber in an annular sheet sufficiently thin to effect such a thorough mixing of said charge that substantially 30 complete combustion will result on ignition, a valveless sub-piston for preventing said charge from commingling with the burned gases of the previous explosion, and means for controlling said sub-piston.

35

21. An internal combustion engine, comprising in combination a cylinder terminating in a combustion chamber, the combustion-chamber end of said cylinder being counterbored, a power piston arranged to 40 reciprocate in said cylinder, a sub-piston located between said power piston and said combustion chamber, and means for positively controlling said sub-piston.

In testimony whereof I have hereunto 45
subscribed my name this 10th day of May,
1918.

FRED HENRY GILE.
